UNITED STATES PATENT OFFICE.

ALFRED LOUIS EDOUARD CASPAR, OF LA GARENNE-COLOMBES, FRANCE.

ADVERTISING MEANS.

SPECIFICATION forming part of Letters Patent No. 630,486, dated August 8, 1899.

Application filed October 9, 1897. Serial No. 654,679. (No model.)

To all whom it may concern:

Be it known that I, ALFRED LOUIS EDOUARD CASPAR, gentleman, of La Garenne-Colombes, (Department de la Seine,) in the Republic of France, have invented certain new and useful Improvements in Advertising Means, (patented in Great Britain, No. 20,382, dated July 23, 1898, and in France, for fifteen years, dated June 18, 1897;) and I do hereby declare that the following is a full and exact description thereof, reference being made to the accompanying drawings.

This invention relates to means for advertising applied to toilet-paper rolls, books, or the like, but which will be applied to independent sheets of paper placed alternately with the sheets of toilet-paper and which are so perforated as to render the use of such special paper impossible for toilet purposes.

Among the advantages of perforating the advertising strip or sheet as described are that thereby the use of paper carrying printing-ink for toilet purposes is avoided and only plain paper used for that purpose, as is very desirable. Further, the advertising-sheets (in the case of a roll) not being subject to use will naturally, at least a part of the time, remain attached to the strip and exposed while several toilet-sheets are removed, thereby increasing the value of the advertisements. Sometimes the advertising-sheets will be torn off with the toilet-sheets, in which case the advertisement would not remain exposed, as will be evident.

The toilet-paper and the perforated advertising-paper are of any color and may be arranged together in a roll on the same spindle or like the leaves of a book—that is to say, one above the other, so that the leaves of perforated advertising-paper are placed alternately with the sheets of toilet-paper.

In the accompanying drawings, in which I have shown toilet-paper arranged in a roll and also arranged in a manner similar to the leaves of a book, Figure 1 is a front view of a roll of toilet-paper and of perforated advertising-paper. Fig. 2 is a vertical section on the line 1 2, Fig. 1. Fig. 3 is a front elevation of a book made up of the two kinds of paper. Fig. 4 is a section on the line 3 4, Fig. 3.

By referring to Figs. 1 and 2 it will be seen that the roll of toilet advertising-paper is made

up by rolling together on the same spindle a strip of paper *b*, forming a succession of sheets of toilet-paper only, and a strip of paper *c*, 55 placed underneath the first-named strip and having perforations *o* distributed in the advertising part thereof between the predetermined lines (perforated or not) at which the sheets are designed to be torn off from time 60 to time and which prevent the use of this paper for toilet purposes. These rolls of paper and the spindle may be mounted upon a small vertical board *d*, which is fixed to the wall. In this case the spindle *a* will preferably be 65 one of the sides of a rectangle, of which the opposite side *a'*, serving as a pivot, will be held in a longitudinal groove provided for that purpose in the rear face of the said board. A flat spring *r*, attached at one end to the 70 board, exerts constant pressure upon the said roll, so as to prevent the strips *b* and *c* from being rolled off too quickly.

Figs. 3 and 4 show a book made up of sheets of toilet and of advertising paper. On a small 75 board or cardboard *f* are placed alternately one above the other the sheets of toilet-paper *g* and of perforated advertising-paper *h*. A strip of cardboard *f'* is placed on the top of the pile of papers thus formed and at one end 80 of the same, and the said strip *f'* is secured to board *f* either by nails, which pass through the ends of papers *g* and *h*, or in any other suitable manner, but so as to hold the said ends firmly pressed between the said strip of 85 cardboard *f'* and the board *f*, so that the papers *g* and *h* may be successively torn off without carrying with them the said ends.

Both in the case of the roll form and book form there may be any desired quantity of 90 toilet-paper and of perforated advertising-paper placed together alternately. Between two strips or between two sheets of toilet-paper there may be placed two or more strips or sheets of advertising-paper, and in the same 95 manner between two strips or two sheets of advertising-paper there may be placed one, two, or more strips or sheets of toilet-paper.

I reserve the right to use my toilet-paper together with perforated advertising-paper 100 with any and every system of distributor of toilet-paper whether the system be automatic or not.

Having thus described my invention, what

I claim as new, and desire to secure by Letters Patent, is—

1. The combination with a series of sheets of toilet-paper, and alternating therewith paper containing advertisements, the latter paper being adapted to be torn away on predetermined lines; and having holes *o* in the bodies of the advertising-sheets, whereby removal of sheets of toilet-paper exposes the perforated advertising-sheets which are made unsuitable for toilet use by the said holes *o*, as set forth.
2. The combination with a suitable spindle, of a strip of toilet-paper adapted to be torn off in suitable lengths or sheets, and a strip of advertising-paper alternating with the toilet-paper and adapted to be torn off in sheets; said advertising-paper having perforations *o* in the bodies of the sheets between the lines

where the sheets are torn off, said perforations rendering the advertising-paper unfit for toilet use.

3. The combination with a suitable spindle, of a strip of toilet-paper and a strip of paper containing advertisements both wound together upon said spindle and provided with lines of perforations, whereby said strips are divided into detachable leaves, the leaves containing the advertisements being perforated between their perforated dividing-lines being thereby rendered non-usable for toilet purposes, substantially as set forth.

In witness whereof I have hereunto set my hand in presence of two witnesses.

ALFRED LOUIS EDOUARD CASPAR.
